UNITED STATES PATENT OFFICE.

MARTIN E. ANDERSON, OF DENVER, COLORADO.

TIRE LOCK.

Application filed April 10, 1924. Serial No. 705,431.

To all whom it may concern:

Be it known that I, MARTIN E. ANDERSON, a citizen of the United States, residing at Denver, the city and county of Denver, and State of Colorado, have invented certain new and useful Improvements in Tire Locks; and I do declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to improvements in locks for automobile tires, of the type described and claimed by me in my application, Serial No. 622,679, filed November 3, 1923.

The object of this invention is to produce a lock that can be readily applied to and removed from a threaded member such as a bolt or valve stem, but which, when in place, can be removed, if at all, only with great difficulty, unless the proper key is employed.

My invention can be best described and will be most readily understood when reference is had to the accompanying drawing in which the preferred embodiment thereof is shown, and in which:

Fig. 1 is a section taken on line 1—1, Fig. 3, with the key removed;

Fig. 2 is a section similar to that shown in Fig. 1 and shows the key in place and the lock in position to be applied to or removed from a threaded member;

Fig. 3 is a section taken on line 3—3, Fig. 2;

Fig. 4 is a top plan view of the locking nut;

Fig. 5 is a side elevation of the nut shown in Fig. 4;

Fig. 6 shows my lock in place on a valve stem for the purpose of locking a demountable rim in place;

Fig. 7 shows my lock used for locking two members together;

Fig. 8 shows a bolt to which my lock is applied; and

Figs. 9 and 10 are a plan view and a side elevation, respectively, of a modified form of deformed nut.

My lock consists of a cylindrical member provided with an enlarged cylindrical chamber 2 for the reception of the locking

nut 3, and washer 4. One end of the chamber 2 is closed by a washerlike member 5 that is seated in a rabbet 6 and held in place by the end 7 that is spun over the inclined edges thereof. The other end of the chamber 2 is closed by the wall 8 that is provided with a threaded opening 9. The nut 3 is somewhat smaller in diameter than the chamber 2 and has a central opening threaded for engagement with a bolt 10 or a valve stem 11. The nut is cut on one side, as indicated by numeral 12, and bent into helical form in the manner shown in Fig. 5. The cut 12 is made after the opening has been threaded and the nut is bent after the cut is made. It is therefore evident that when the nut is held in the position shown in Fig. 2, the threads will assume their normal relation, but if it is left free, it will tend to assume the shape shown in Figs. 1 and 5. The washer 4 rests upon the nut between it and the wall 8 so that the nut cannot be engaged by a sharp tool when the lock is in place on a bolt. My key consists of a tube 13 having an inside diameter slightly greater than the root diameter of the threads in the nut, so that it can be slipped over any bolt to which the lock may be applied. One end 7 of the key is threaded, as indicated at 14, so as to engage the threads in the opening 9. The action of the key is to clamp the nut against the end member 5 with sufficient force to cause it to assume its original shape in the manner shown in Fig. 2. When the key is in place and the nut clamped in the position shown in Fig. 2, the lock may be threaded onto a bolt or removed therefrom in the same manner as any ordinary nut. Instead of making the nut in the manner described it may be formed as shown in Figs. 9 and 10, which show a nut cut partly across, as indicated by 12a. The cut is made after the nut is threaded and the sides are then spread apart as shown.

Let us now suppose a case in which the lock has been screwed onto a bolt and the key removed. The nut, which must be made of some resilient material, will tend to assume the distorted shape shown in Figs. 1 and 5. This will cause it to bind on the bolt. If member 1 is rotated, it will not rotate the nut, as the friction between the bolt and the nut is greater than any friction that can be developed between the nut and its enclosing casing. The lock can therefore not be removed from the bolt until the

key 13 is inserted and screwed down with sufficient force to flatten the nut and to remove the tension that causes it to bind on the bolt.

5 If an unauthorized person should attempt to pick the lock by inserting a sharp instrument between the bolt and the sides of hole 9, he will merely engage the washer 4, which is freely rotatable. By making the threads 10 in hole 9 and on the end of the key 13 different and some right and others left, a large number of combinations can be obtained, which would make it highly improbable that an unauthorized person will accidentally obtain a key that will open the lock. The threads, moreover, may be made special so that no stock taps or dies can be found to cut a proper thread on the key and in this manner a very safe lock can be produced.

20 In Fig. 6 I have shown my lock in place on a valve stem 11, which passes through the demountable rim 15 and felloe 16 of an automobile wheel. The ordinary nut 17 and dust cap 18 can be used in the usual manner.

25 In Fig. 7 I have shown my lock applied to a bolt 10 that can be used for any purpose, such as clamping two members 19 and 20. An ordinary nut 21 can be applied to 30 the bolt to produce the desired clamping action. In Fig. 8 I have shown a bolt that may be used for any purpose. The bolt has a cotter pin 22 that positively prevents loss of the nut 21.

35 My invention depends primarily on the use of a deformed nut that will bind on a threaded bolt and which is enclosed and freely rotatable in a casing. The casing is so constructed that a key may be associated 40 therewith for the purpose of clamping the nut so as to hold it non-rotatably in normal shape. I am aware that the nut may be deformed in other ways than that shown, and I desire to cover broadly the use of a deformed nut in combination with the other parts shown.

45 Having now described my invention, what I claim as new is:

1. A locking device comprising, in combination, a casing having a cylindrical chamber, said chamber being provided with a top and a bottom, each of which has an axial opening of less diameter than the chamber, the opening in the top being threaded, a nut 50 within said chamber, said nut being freely movable therein, and of greater diameter than the opening and a tubular threaded member operatively related to the top and adapted to force the nut against the bottom 55 and to clamp it against rotation.

2. A locking device comprising, in combination, a casing having a cylindrical chamber, said chamber being provided with a top and a bottom, each of which has an axial 60 opening of less diameter than the chamber,

the opening in the top being threaded and adapted to receive a threaded clamping member, a nut within said chamber, a clamping member operatively associated with the threads of the opening, and a washer between the nut and the top, said casing, nut and washer being freely movable with respect to each other, the nut and washers being of greater diameter than the openings.

3. A locking device comprising, in combination, a casing having a cylindrical chamber, said chamber being provided with a top and a bottom, each of which has an axial opening of less diameter than the chamber, the opening in the top being threaded, a nut within said chamber, a washer between the nut and the top, said nut and washer being freely movable with respect to each other and the casing, the nut and washer being of greater diameter than the openings, and a tubular clamping member operatively associated with the threaded opening in the top and adapted to force the nut against the inner surface of the bottom so as to clamp the nut against rotation.

4. A locking device comprising a tubular member provided with a cylindrical opening, one end of said opening being of smaller diameter than the other end whereby a shoulder is formed, a circular nut rotatably mounted in the larger end of said opening; a washer between the nut and the shoulder, means for preventing the nut from being removed from the opening, and means for clamping said nut against relative rotation 100 with respect to the tubular member, said means comprising a tubular key having a threaded connection with the interior of that portion of the cylindrical opening having the smaller diameter, said key being 105 adapted to engage the nut and clamp the same against rotation in the tubular member.

5. In a locking device adapted to be turned entirely onto a threaded stem, in combination, a casing having a chamber, a nut freely rotatable within said chamber, said casing having an abutment, for engaging the nut to limit its longitudinal movement with respect to the casing, and a tubular key member adapted to be fitted over the threaded stem, said key and casing having threaded engagement with each other, said key being adapted to engage the nut and to force it against the abutment to hold it 110 against rotation with respect to the casing.

6. A lock comprising an externally threaded member, a deformed nut cooperatively connected thereto, a casing for enclosing said nut, said nut and casing being 115 freely rotatable with respect to each other, and means for causing said nut to assume its normal shape and for clamping it against rotation within said casing.

7. A lock adapted to be secured to the 120

threaded end of a bolt, said lock comprising a casing, a nut freely rotatable in said casing, said nut having its threaded surface deformed so as to clamp itself onto the 5 threaded surface of a bolt, and means comprising a tubular member for causing the nut to assume normal shape and for clamping it to the casing.

8. A lock comprising a casing having a 10 cylindrical chamber, a circular nut freely rotatable within said chamber, said nut being deformed, and means for changing the nut to normal shape and clamping it against rotation with respect to the casing, said 15 means comprising a tube adapted to have threaded connection with the casing and to clamp the nut therein.

9. A lock comprising, in combination, a 20 body member having an enlarged cylindrical chamber, one end of said chamber having an internally threaded opening and the other end having an unthreaded opening, said 25 openings being of less diameter than the chamber, a circular nut within said chamber, said nut having a cut through its side and having the adjacent ends distorted, a 30 washer between the nut and the end having the threaded opening, and means for forcing said nut against the end of the chamber having the unthreaded opening so as to 35 change it to normal shape and clamp it against rotation.

10. A lock comprising, in combination, a 35 body member having an enlarged cylindrical chamber, one end of said chamber having an internally threaded opening and the other end having an unthreaded opening, said 40 openings being of less diameter than the chamber, a circular nut within said chamber, said nut having a cut through its side and having the adjacent ends distorted, a 45 washer between the nut and the end having the threaded opening, and means for forcing said nut against the end of the chamber having the unthreaded opening, so as to 50 change it to normal shape and clamp it against rotation, said means comprising a tubular key having its outer surface provided with threads for engaging the sides of the threaded opening.

11. A locking device comprising a member provided with a cylindrical opening, one 55 end of said opening being of smaller diameter than the other end, whereby a shoulder is formed, a cylindrical distorted nut rotatably mounted in the larger part of said opening, a freely movable washer between the

nut and the shoulder, means secured to said member for preventing the nut from being removed from said opening, and means for 60 causing the nut to assume normal shape and for clamping it against relative rotation with respect to said member.

12. A locking device comprising a member provided with a cylindrical opening, one 65 end of said opening being of smaller diameter than the other end, whereby a shoulder is formed, a cylindrical distorted nut rotatably mounted in the larger part of said opening, a freely rotatable washer between 70 the nut and the shoulder, means secured to said member for preventing the nut from being removed from said opening, and means for causing the nut to assume normal shape and for clamping it against relative rotation with respect to said member, 75 said means comprising a tubular key having a threaded connection with the interior of that portion of the opening having the smaller diameter.

13. A locking device comprising a casing having a cylindrical opening, one end of said casing having a transverse wall member provided with a threaded opening of less diameter than the chamber, the other end of 85 said casing having a rabbet, a washer having its edge located in said rabbet, a portion of the metal of the casing extending over the edge of the washer so as to hold it in place, a nut rotatably mounted in said 90 chamber, a freely movable washer between the nut and the transverse wall, said nut and washer being of greater diameter than the openings, and means for clamping the nut against rotation.

14. A locking device comprising, in combination, a casing having a chamber, said 95 chamber being provided with a top and a bottom, said top and bottom each having an opening, which is substantially concentric with the opening in the other, said openings being of less diameter than the corresponding dimension of the chamber, the opening in the top member being threaded for the reception of a threaded clamping 100 member, a nut freely movable within the chamber, said nut being of greater diameter than the openings, and means comprising a threaded member for clamping the nut against rotation.

In testimony whereof I affix my signature.

MARTIN E. ANDERSON.
